UNITED STATES PATENT OFFICE.

JOSHUA NORRISH, OF SAN FRANCISCO, CALIFORNIA.

ROASTING FURNACE.

Application filed September 26, 1922. Serial No. 590,714.

To all whom it may concern:

Be it known that I, JOSHUA NORRISH, a citizen of the United States, residing at the city and county of San Francisco and State of California, have invented new and useful Improvements in Roasting Furnaces, of which the following is a specification.

This invention relates to a roasting furnace, and especially to a vertical shaft type 10 of furnace employing a gravity feed.

The object of the present invention is to generally improve and simplify roasting furnaces of the stack type; to provide a furnace which is adapted for roasting and de- 15 sulphurizing ores, and also for retorting such products as oil shale and the like; to provide a furnace which is continuous in operation and in which the material is fed by gravity from the point of intake to the 20 point of discharge and maintained under constant movement and agitation throughout the entire roasting operation; and further to provide a novel arrangement of electric heating elements whereby heat may be di- 25 rectly and efficiently applied to the ore or other material being treated. Other objects will hereinafter appear.

One form which my invention may assume is exemplified in the following description 30 and illustrated in the accompanying drawings, in which—

Fig. 1 is a central, vertical, longitudinal section through the furnace.

Fig. 2 is a cross section on line 2—2, 35 Fig. 1.

Fig. 3 is a perspective view of one of the baffle supports.

Fig. 4 is a perspective view of the uppermost baffle member.

40 The furnace as shown in Figs. 1 and 2 is a so called stack furnace. It is circular in cross section. It consists of an outer wall constructed of common brick and an inner wall constructed of metal or a refractory material as desired. The interior or roasting chamber formed is also cylindrical in cross section, and disposed therein are two upright members as indicated at 2 and 3. These members extend from the top to the 45 bottom of the furnace and will hereinafter be referred to as baffle supports. Both members are identical in construction and they are particularly illustrated in a perspective view, see Fig. 4. Each baffle support is pro- 50 vided with a series of angularly disposed supporting shelves 4, which are staggered

with relation to each other, see Fig. 1, and disposed intermediate these shelves is a series of hollow baffle member or plates, such as indicated at B. These baffle plates are identical in construction and are disposed in opposition to each other to form a tortuous inclined passageway through which the ore is fed by gravity during the roasting operation. Each baffle member, (see Fig. 4,) consists of a bottom section 7, a top section 7^a, side sections 8, and an end section 9. The side sections are bevelled off at one end, as indicated at 10, and as such form supports for one end of the succeeding baffle member. 60 The bottom section of each baffle is provided with a discharge opening, as shown at 11, through which the ore or material being treated discharges from one baffle member to another. The baffles, together with the 65 members 2 and 3, supporting the same, are removable and a demountable iron dome 12 is therefore employed. This dome may be covered with a refractory material as desired, and is secured by anchor bolts, as 70 indicated at 13. This construction is im- 75 portant as it permits the furnace to be opened from time to time for inspection, repairs or otherwise, and broken baffle plates or heating elements hereinafter to be 80 referred to may therefore be quickly and 85 easily reached when desired.

The furnace here illustrated is particu- 90 larly adapted for roasting ores, such as cinnabar, zinc ores and the like. It may also be employed for desulphurizing ores, and it may furthermore be applied as a retort when handling oil shales and similar products. The furnace is continuous in operation; the ore being delivered to the 95 uppermost baffle through a hopper not shown through a pipe 14. The ore deposited on the inclined bottom section of the uppermost baffle runs by gravity down to the discharge opening 11 and it is then deposited on the second baffle. This is inclined in the opposite direction and the ore will therefore travel in a tortuous path from the top to the bottom before it can discharge. The 100 heat is supplied to the furnace by means of electricity, that is four vertically disposed electric ribbon heating units are employed as indicated at 15, 16, 17 and 18. These ribbons extend from end to end of the fur- 105 nace and supply the heat whereby the interior of the furnace chamber is raised to any 110 temperature desired, and whereby heat is

imparted to the baffle members B, over and through which the ore passes. The fumes liberated during the roasting of the ore pass upwardly and discharge through a pipe 19, 5 which leads to a condenser of suitable construction not here shown. The ore when roasted discharges from the lowermost baffle and passes out through the discharge opening indicated at 20, a sliding gate 21 being here employed as a closure whenever required. The discharging material may be delivered to a conveyor not here illustrated and may in this manner be removed from the furnace to any point of discharge desired. 10 15

The ribbon elements indicated at 15, 16, 17 and 18, are supported by terminal posts as indicated at 22. These posts extend through the walls of the furnace and are insulated 20 therefrom in the usual manner. They are otherwise connected with a suitable source of current supply.

The present invention has numerous advantages when comparison is made with 25 types of similar construction. First of all it will be noted that all parts exposed to high temperature are stationary and as such may be constructed of refractory material, which can withstand high temperatures 30 when required. The baffle members employed are all disposed on an incline, thus permitting a gravity feed, this being of particular importance as it eliminates all mechanical feeding devices usually employed and which are readily destroyed by 35 high furnace temperatures. By increasing and decreasing the incline of the baffles, the time element required when roasting ore in particular may be changed, and as the ore 40 is maintained under constant movement and is agitated when it drops from shelf to shelf, it can readily be seen that all ore particles will be exposed to the heat of the furnace and thereby uniformly acted upon. The 45 cost of operating a furnace of this character should be comparatively small as the heat is electrically applied and as such does not require air drafts which carry away a great portion of the heat. It is furthermore obvious that a furnace of this character can be 50 efficiently insulated against heat losses and as such should increase the general efficiency of the same. The interior construction of the furnace is such that accessibility for inspection and repairs is permissible by merely removing the dome 12, and as practically all parts employed in the interior construction are identical in size, shape, 55 spare parts may be maintained.

60 The inner end of the feed pipe indicated at 14 is perforated as shown to permit escape of gases which might form. Other minor details of construction may be resorted to within the scope of the appended 65 claims. I similarly wish it understood that

the materials and finish of the several parts employed may be such as the experience and judgment of the manufacturer may dictate or various uses may demand.

In instances where sulphur is encountered 70 and where the ore or material treated contains moisture, it is obvious that metal objects would be detrimentally affected by the sulphurous fumes produced. In cases of this character it is desirable to isolate the 75 heating ribbons 15, 16, 17 and 18, or in other words to prevent the fumes from reaching the same. This is accomplished by cementing or otherwise joining the baffle members where they connect to prevent escape of gas, 80 and also by enclosing the same from top to bottom between the members 2 and 3 in a pair of side plates 31 and 32, which also extend from the top to the bottom of the furnace. The plates 31 and 32, together with the plates 2 and 3, form a rectangular passage from the top to the bottom of the furnace, interior of which the baffle members B are mounted. This rectangular passage, together with the baffle members, is gas tight 85 and communicates with the discharge pipe 19 at one end and with the discharge opening 20 at the opposite end. The heating elements referred to are thus protected. 90

Having thus described my invention, 95 what I claim and desire to secure by Letters Patent is—

1. In a furnace of the character described having a vertical cylindrical roasting chamber, vertical walls arranged within the roasting chamber and forming a rectangular passage and fitted at their corners against the walls of the cylindrical roasting chamber and forming intervening spaces for the reception of heating elements and a series of oppositely inclined baffle plates arranged within the rectangular passage and forming a tortuous passage through which the material to be roasted may flow by gravity from the upper to the lower end of the roasting chamber. 100 105 110

2. In a furnace of the character described having a vertical roasting chamber, vertical walls arranged within the roasting chamber and forming a rectangular passage and oppositely inclined hollow baffle members fitted together and mounted within the rectangular passage and forming interiorly of them a tortuous passage through which the material to be roasted may flow by gravity from the upper to the lower end of the roasting chamber. 115 120

3. In a furnace of the character described having a vertical roasting chamber, vertical metallic walls arranged within the roasting chamber and forming a rectangular passage, two of the opposite walls being provided with supporting shelves arranged in staggered relation, and a series of oppositely inclined hollow baffle members fitted to 125 130

gether and supported upon the said shelves and forming interiorly of the said baffle members a tortuous path down which the material to be roasted may flow by gravity 5 from the upper to the lower end of the roasting chamber.

4. In a furnace of the character described having a vertical roasting chamber four vertical walls within the roasting chamber and 10 forming a rectangular passage and oppositely inclined tapering hollow baffle members fitted together at their ends and provided thereat with communicated openings and forming a tortuous passage interiorly 15 of the baffle members through which the material to be roasted may flow from the upper to the lower end of the roasting chamber.

5. In a furnace of the character described 20 having a vertical cylindrical roasting cham-

ber, four vertical walls arranged within the roasting chamber and forming a rectangular passage and contacting at their corners with the walls of the cylindrical roasting chamber and forming intervening spaces for the reception of heating means, two of the opposite walls being provided at intervals with shelves, the shelves of one wall being staggered with relation to the shelves of the opposite wall, and hollow oppositely inclined tapering baffle members supported upon the said shelves and fitted together at their adjacent ends and provided thereat with communicating openings and forming a tortuous passage through which the material to be roasted may flow by gravity from the upper to the lower end of the roasting chamber.

JOSHUA NORRISH.
